UNITED STATES PATENT OFFICE.

SAMUEL G. FRANKLIN, OF NEW YORK, N. Y., ASSIGNOR, BY DIRECT AND MESNE ASSIGNMENTS, OF ONE-HALF TO HERBERT G. UNDERWOOD, OF NEW YORK, N. Y., AND ONE-HALF TO WILLIAM S. BRIAN, OF MEMPHIS, TENNESSEE.

CASTING APPARATUS.

No. 894,824.

Specification of Letters Patent.

Patented Aug. 4, 1908.

Application filed March 26, 1907. Serial No. 364,705.

To all whom it may concern:

Be it known that I, SAMUEL G. FRANKLIN, a citizen of the United States, residing in the borough of Manhattan, of the city of New York, in the State of New York, have invented certain new and useful Improvements in Casting Apparatus, of which the following is a specification, reference being had to the accompanying drawing, forming a part hereof.

Various forms of apparatus have been devised hitherto for the purpose of facilitating the rapid casting of metals under pressure, such forms of apparatus being concerned mainly with the means for transferring the molten metal from the melting pot or reservoir to the mold and for supporting and manipulating the mold.

The object of the present invention is to still further improve such apparatus and particularly with a view to obtaining increased speed and convenience in operation, to the preservation as far as possible of the metal which is introduced into the mold at each operation from immediate contact with the atmospheric air and gases about the melting pot or reservoir and its furnace, to the filling of the mold at each operation with metal which is drawn from a level below the surface of the metal in the melting pot or reservoir so that it shall be free from dross, and to the rapid operations of the entire apparatus particularly the movement of the mold.

In accordance with the invention there is disposed within the melting pot or reservoir, in which the level of the molten metal is preferably maintained practically constant through the addition of fresh metal from time to time, a pressure chamber which, having a nozzle adapted to deliver molten metal to the ingate of the mold and being itself stationary with respect to the reservoir, is itself charged with molten metal drawn from a point below the surface of the metal in the reservoir, and from which the charge of metal is then delivered to the mold under suitable fluid pressure which is preferably supplied within the pressure chamber by the admission of air under pressure. The charging of the pressure chamber is effected by submerging the nozzle in a portion of the contents of the reservoir drawn therefrom at a point below the surface level. The mold is so supported and arranged as to be moved up to

the nozzle and to make a tight joint therewith during the discharge of the metal from the pressure chamber into the mold and then to be moved away in order that it may be opened and the casting removed, while during the retiring movement of the mold the recharging of the pressure chamber is effected.

The invention will be more fully described hereinafter with reference to the accompanying drawing which, for the purpose of illustration and explanation of the nature of the invention, shows, partly in elevation and partly in longitudinal section, one form of apparatus which embodies the invention.

In the apparatus shown in the drawing the melting pot or reservoir *a* is shown as suitably supported, it being assumed that there is supplied a suitable source of heat, not shown, to maintain the metal in the reservoir in a molten condition and at the desired temperature. Within the reservoir *a*, preferably so as to be fully submerged therein, is placed a supplemental pot or pressure chamber *b*, completely closed and provided with a connection *c* to a source of fluid pressure, such as an air compressor, the connection *c* having a suitable valve *d* through which the fluid may be admitted under control to the pressure chamber and through which also the pressure in the chamber *b* can be relieved when desired. The chamber *b* is also provided with a nozzle *e*, preferably extended from the lower part of the chamber *b* to a point above the level of the molten metal in the reservoir *a* and beyond the wall of such reservoir so that the ingate of the mold may make a tight joint therewith. The mold *f*, which may be of any suitable construction, is supported by a carrier which comprises, in the construction shown, two parts *g* and *g'* which may be connected, to form a single structure, by any suitable means, such as a link *g''*. The member *g* supports the ingate *f'* of the mold and the carrier as a whole is mounted to move toward and from the nozzle *e*, being supported, as shown, upon a suitable track or way *h*. The member *g* of the carrier is provided with a gear *i* and crank *i'*, the gear meshing with a rack *k* on the track *h*, so that the carrier can be moved readily toward and from the nozzle and held tightly against the nozzle during the filling of the mold.

For the recharging of the pressure cham-

ber *b* there is formed in the wall of the reservoir *a* and considerably below the surface level of the molten metal therein, a port *a'* and outside of such wall and covering the 5 port is arranged a charger *l* which is adapted to move vertically. In the position of the charger *l* shown in the drawing the molten metal from the reservoir fills the charger through the port *a'*, but when the charger is 10 raised, as hereinafter described, the port *a'* is covered by the lip *l'* of the charger, so that no more metal shall escape from the reservoir, and the extremity of the nozzle *e* of the pressure chamber *b* is submerged in the molten 15 metal in the charger so that the pressure chamber *b* will be recharged from the charger through the nozzle *e*, the valve *d* being then turned so that the pressure in the chamber *b* is relieved.

20 For convenience, the charger *l* may be raised and lowered through the movement of the mold from and toward the nozzle. For this purpose the member *g'* of the mold carrier is provided with a roller *g* which is 25 adapted to coöperate with one end of a lever *m*, the other end of which supports, through a link *m'*, the charger *l*. As the mold carrier approaches the rearward limit of its movement the charger *l* is raised, through the described connections, for the purpose of re- 30 charging the chamber *b* with molten metal, and as the mold carrier approaches the nozzle the charger is lowered to permit it to be re-filled with molten metal from the reservoir 35 and also to permit the ingate of the mold to be brought into close contact with the extremity of the nozzle.

It will be understood that when the ingate 40 of the mold is in contact with the extremity of the nozzle, it can be held in that position by any suitable means, such as a latch *n* arranged to coöperate with a stud *n'* on the carrier *g*, and that the valve *d* is manipulated, at the proper time, so as to cause the dis- 45 charge of the molten metal from the chamber *b* through the nozzle *e* into the mold *f*. It will be understood, also, that various changes in details of construction and arrangement can be made, according to the 50 conditions of use of the apparatus, and that the invention is not to be restricted to the particular construction and arrangement shown.

I claim as my invention:

55 1. In a casting apparatus, the combination with a reservoir for molten metal, of a pressure chamber provided with means for delivering molten metal to a mold, and a movable charger adapted in one position to 60 receive molten metal from the reservoir and in another position to deliver it to the pressure chamber.

2. In a casting apparatus, the combination of a reservoir for molten metal, a pressure chamber having a nozzle adapted to de-

liver molten metal to the mold, and a movable charger to receive molten metal from the reservoir and deliver it to the pressure chamber, the reservoir being adapted to communicate with the charger below the surface of the molten metal.

3. In a casting apparatus, the combination of a reservoir for molten metal, a pressure chamber located within the reservoir and having a nozzle above the surface of the molten metal and adapted to deliver molten metal to the mold, and a movable charger to receive molten metal from the reservoir and deliver it to the pressure chamber, the reservoir being adapted to communicate with the charger below the surface of the molten metal in the reservoir.

4. In a casting apparatus, the combination of a reservoir for molten metal having in its wall a port below the surface of the molten metal, a pressure chamber located within the reservoir and having a nozzle projecting outside of the reservoir and above the surface of the molten metal therein and adapted to deliver molten metal to the mold, and a movable charger outside of the reservoir and adapted to receive molten metal through the port in the wall thereof and to transfer the molten metal to the pressure chamber through said nozzle.

5. In a casting apparatus, the combination with a vessel to contain molten metal, and a pressure chamber provided with a nozzle of a mold carrier movable toward and from the nozzle, a movable charging device to receive molten metal from the vessel and deliver it to the pressure chamber, and common means for actuating both the mold carrier and the charging device.

6. In a casting apparatus, the combination of a reservoir for molten metal, a pressure chamber located within the reservoir and below the surface of the molten metal therein and having a nozzle extended from its lower portion upward beyond the wall of the reservoir above the surface of the molten metal, said reservoir having a port in its wall below the surface of the molten metal, and a charger arranged to slide vertically against said wall of the reservoir and to be filled with molten metal through the port in its lower position and to surround the nozzle in its upper position and charge the pressure chamber through said nozzle.

7. In a casting apparatus, the combination of a reservoir for molten metal, having a port in its wall below the surface of the molten metal, a pressure chamber having a nozzle above the surface of the molten metal outside of the reservoir, a charger arranged to move vertically against the wall of the reservoir and to communicate with said port in its lower position and to surround said nozzle in its higher position, a mold carrier arranged to move toward and from the nozzle,

and means supporting the charger and acted upon by the carrier in its movements to raise and lower the charger.

8. In a casting apparatus, the combination of a reservoir for molten metal having a port in its wall below the surface of the molten metal; a pressure chamber having a nozzle above the surface of the molten metal outside of the reservoir; a charger arranged to move vertically against the wall of the reservoir and to communicate with said port in its lower position and to surround the nozzle in its higher position, a mold carrier arranged to move toward and from the nozzle, and a lever to support the charger at one end and having its other end acted upon by the carrier in its movements to raise and lower the charger.

This specification signed and witnessed this 12th day of March, A. D., 1907.

SAMUEL G. FRANKLIN.
